UNITED STATES PATENT OFFICE.

JOSEPH LEE ROUSSEAU, OF BROOKLYN, NEW YORK, ASSIGNOR TO MERTGENTHALER LINOTYPE COMPANY, A CORPORATION OF NEW YORK.

METHOD AND APPARATUS FOR PRODUCING PRINTING SURFACES.

Application filed October 17, 1924. Serial No. 744,103.

This invention relates to the production of printing surfaces, and has reference more particularly to the formation of the printing surfaces of rubber stamps, the object of the 5 invention being to enable the formation of the rubber type or line of types to be carried out by the use of formative matrices such as are employed in the well known commercial linotype machines. In accordance with my 10 invention, such matrices may be employed either individually to produce separate rubber type or in series to produce a type line. In the present instance, the matrices are so constructed that they may be employed 15 in their usual environment in the regular commercial linotype machine, which is particularly desirable for obvious reasons. In carrying out the invention, there is employed a suitable matrix containing in its 20 edge a negative cameo character; a mold is then made from this character by casting type metal thereagainst, said mold thus containing in its face a positive intaglio character; and into this mold, rubber or other 25 suitable plastic material is forced to produce a negative cameo printing character, which when impressed on a suitable receiving surface will give a positive print.

In practising the invention in connection 30 with a linotype machine, the machine is equipped with conventional matrix bodies formed with negative cameo characters, which matrix bodies are assembled in line in the usual way by the manipulation of the keyboard 35 mechanism, and the line thereafter delivered between the customary clamping jaws which hold the line in operative relation to the regular casting mold. Molten type metal is then, in the well known manner, injected into 40 the mold against the line of formative characters, and as a result there is produced a slug containing in its edge a reproduction of the formative characters but in the form of positive intaglio characters, such slug constituting in effect a metal mold or matrix. 45 Into the mold thus cast, plastic material of which the printing surface is to be formed (for instance soft rubber) is forced, thereby producing a printing surface having negative intaglio characters which will give a positive print.

In the accompanying drawings:

Fig. 1 is a perspective view of a linotype matrix provided with a formative character suitable for the practice of the improved 55 method;

Fig. 2 is an elevation of an assembled line of such matrices showing the formative characters as they appear when the line is presented to receive the cast; 60

Fig. 3 is a sectional elevation showing the matrix line presented to the casting mold and melting pot of a linotype machine; 65

Fig. 4 is a perspective view of the slug resulting from the casting operation; 70

Fig. 5 is a sectional perspective view showing the plastic material, of which the final printing surface is formed, forced into the intaglio characters of the slug of Fig. 4 to form the printing surface; and 75

Fig. 6 is a perspective view of the final printing surface.

The improved method will herein be described as practised in connection with a linotype machine for the production of a 75 line of rubber printing type.

The matrices or matrix bodies A, of conventional form, (see Figs. 1 and 2) are provided in their edges with uninverted negative cameo characters *a*. These matrices A are 80 then assembled in the usual way in a line B reading from right to left as shown in Fig. 2, the line in the present example representing the words "Received payment", and the two groups of matrices being separated by 85 the usual expansible spaceband C which justifies the line. The assembled matrix line is next presented to the face of a slotted mold D, and molten metal is injected into the mold slot and up against the formative 90 characters *a* from a melting pot E as shown in Fig. 3, thereby forming a slug F, as in Fig. 4, containing in its edge a reproduction of the characters of the matrix line but in the form of positive intaglio characters *f*, 95 reading from left to right. The slug thus cast forms in effect a metal mold or matrix adapted to receive the plastic material (for instance rubber) of which the final printing surface is to be formed. This plastic material G, is now forced by suitable means into the intaglio characters *f*, see Fig. 5, and 100

the material is built up to form a strip or plate H bearing on its face a line of negative cameo characters h reading from right to left and constituting the final rubber printing surface, which when applied against a suitable impression surface will give a positive print as usual.

By the employment of linotype matrices as above described, the method may be carried out in a simple effective and uniform manner without the inconvenient, laborious and troublesome practices heretofore followed in making up the mold or form in which the rubber material is cast. Thus, the matrix line is speedily set up by the manipulation of the finger keys of the keyboard, and a metal slug of definite and uniform dimensions is cast from the assembled matrices and serves as a mold into which the rubber material is forced to produce the final printing surface. This method of procedure is a great improvement over that now practised for the production of the printing surfaces of rubber stamps, such practice involving the use of individual male type which are set into line, the line surrounded by a dam or guard, and a plastic mass of plaster of Paris made up and pressed into the guard against the type lines so as to form a matrix or mold to receive the rubber material. By the improved method of operation, no treatment of the matrix line, such as the provision of a guard or dam is necessary to enable the slug or mold to be cast thereagainst, and the untidy operation necessary to make up a matrix of plaster of Paris is dispensed with, and a metal mold or slug of definite dimensions is cast directly against the assembled matrices, and produces a mold into which the rubber material is forced to form the final rubber printing surface.

It will be understood that the same steps will be followed in the practice of the improved method when the parts are manipulated by hand, as may be done if preferred. It should also be understood that the matrices, instead of being used in series as above described, may be used individually to produce individual mold members which in turn may be used singly for the production of individual rubber type or in series for the production of an integral line of type. Such

variations of the invention will readily suggest themselves to those skilled in the art without departure from its scope.

While the present invention has been herein shown and described for the production of a rubber printing surface, it is pointed out that it is equally applicable for the production of any surface which requires the use of negative cameo printing type. It should also be observed that the cast metal slug F, which contains positive intaglio characters may be useful in various other connections for the production of printing surfaces, as for example for offset printing.

Having thus described my invention, what I claim is:

1. The method of producing printing surfaces, which consists in assembling a line of matrices having uninverted negative cameo characters reading from right to left, casting a slug against said characters to form a mold containing a line of positive intaglio characters reading from right to left, and forcing plastic material into said mold to form a printing surface having negative cameo characters.

2. The method of producing a rubber printing type surface, which consists in assembling a line of matrices having uninverted negative cameo characters reading from right to left, casting a metal slug against said characters to form a mold having positive intaglio characters reading from right to left, and forcing rubber into said mold to form a rubber type line having negative cameo characters.

3. The combination with a line or group of matrices formed with uninverted negative cameo characters reading from right to left, and means for casting therefrom a metal slug containing positive intaglio characters reading from left to right.

4. The combination with a line or group of matrices formed with uninverted negative cameo characters reading from right to left, and means for casting therefrom a metal slug containing positive intaglio characters reading from left to right, said slug serving as a mold from which a printing surface may be produced.

In testimony whereof, I have affixed my signature hereto.

JOSEPH LEE ROUSSEAU.
